DRAWER FOR FILING CABINETS

George C. Brainard, Youngstown, Ohio, assignor
to The General Fireproofing Company, Youngs-
town, Ohio, a corporation of Ohio

Application August 1, 1935, Serial No. 34,270

8 Claims. (Cl. 129—26)

This invention relates to drawers for filing cabinets and more particularly to a novel construction having special utility in drawers of the type having a tilting front or drawer head.

One of the objects of the invention is to provide a spring tensioned front plate or presser leaf mounted within the drawer adjacent the drawer head to prevent the drawer contents falling forward when the drawer head is tilted outwardly as the drawer is pulled open, but which may be readily moved or swung outwardly by manual finger pressure to release the drawer contents and permit ready removal thereof.

Another object is to provide safety means operating with the pressure plate for preventing the drawer head from being forced open when the filing space is full or crowded and the drawer is closed. That is to say, while the front plate or presser leaf is capable of movement independently of the drawer head when the latter is tilted forward, nevertheless, when the filing compartment becomes crowded the presser leaf cooperates with the drawer head holding means to prevent accidental opening of the closed drawer head due to the expansive force of the filed material. In that connection, the safety means also has a compressive effect on the plate to cause the same to act as a compressor under these conditions.

With the above and other objects in view which will more readily appear as the nature of the invention is better understood, the same consists in the novel features of construction, combination and arrangement of parts hereinafter more fully described, illustrated and claimed.

A preferred and practical embodiment of the invention is shown in the accompanying drawings, in which:—

Figure 1 is a vertical sectional view of a drawer embodying the present invention, a portion of the drawer head being shown in side elevation, and in closed position.

Figure 2 is a view similar to Figure 1 showing the drawer head tilted to open position.

Figure 3 is a view similar to Figure 1 wherein the drawer head is closed but the compartment between the presser leaf and the space regulator is overcrowded with filing material.

Figure 4 is a top plan view of the construction shown in Figure 2.

Figure 5 is a vertical sectional view taken on the line 5—5 of Figure 1.

Figure 6 is a perspective view of the drawer head holding mechanism which constitutes a part 55 of the safety means.

Similar reference characters designate corresponding parts throughout the several figures of the drawings.

According to the embodiment of the invention shown in the drawings, the same includes in its organization, a drawer designated generally as A and which includes the usual bottom and side walls and a back wall (not shown) and having at the front thereof a pivoted drawer head B adapted to tilt outwardly from a vertical position on a pivot B'. Within the drawer A is provided a suitable space regulator or follower C intended to regulate the length of the filing compartment and which cooperates with a novel presser leaf D to maintain the filing material in neat and orderly condition.

The presser leaf or front plate D is located between the drawer head B and the space regulator or follower C and preferably consists of a body of sheet material substantially coextensive with the width of the drawer. The lower end of the presser leaf or front plate D is mounted on a pivot 1 carried in suitable brackets 2 mounted at the front end of the drawer bottom adjacent the pivot B' for the tilting front or drawer head. As will be apparent from Figures 4 and 5, the plate D is preferably forced in one direction by a series of coil springs 3. That is to say, the plate is tensioned to move toward the space regulator C and for the purpose of maintaining the same at an inclination substantially corresponding to that of the space regulator, the upper corners of the plate are provided with the laterally offset ears or lugs 4 (Fig. 4) intended to rest on the upper edges of the side walls of the drawer. The lugs 35 or ears 4 may be provided with suitable cushioning means 5 of felt or rubber to deaden the sound of the plate engaging with the drawer when it is released to permit the springs 3 to exert their force. The presser leaf or front plate D is intended normally to occupy the position shown in Figure 1 when the compartment formed between the plate and the space regulator contains only the proper amount of filing material.

On the other hand, if the filing compartment is crowded with filing material as indicated by the dotted lines in Figure 3, the plate D may assume a more nearly upright position. When the plate is in the position shown in Figure 1, and the drawer head B is closed, that is, in its vertical position, 50 the presser leaf functions merely to serve as a front abutment for keeping the filing material in position. Also, when the drawer is opened by being pulled out of the cabinet and the tilting front is moved forward on its pivot B', as shown in Fig- 55

ure 2, the plate D will still assume the position shown in full lines in Figure 2 to prevent the filing material from falling forward against the inside face of the tilting front or drawer head. 5 However, when it is desired to remove papers filed behind the plate D, it is only necessary to subject the upper edge of the plate D to finger pressure as shown in Figure 2 and pull the same in the direction of the dotted arrow to open up 10 the space between the plate and the regulator C. Therefore, it will be apparent that the front plate or presser leaf D, under normal conditions, operates independently of the tilting front or drawer head B to maintain the filing material in proper 15 condition. However, in the event that the filing material is crowded into the space ahead of the regulator C, the presser plate performs the important function of preventing the expansive force of the overcrowded filing material from forcing 20 the tilting front or drawer head open, as will presently appear more in detail.

Referring to the tilting front or drawer head B, it may be observed that the same is provided with the side wings 6 which are tensioned by the 25 springs 7 in the manner set forth in Patent No. 1,926,503, issued September 12, 1933. The wings 7 are provided with abutments 7^a for engaging a stop abutment 8 on the drawer to limit the outward movement of the drawer head on its pivot 30 B'. As will also be observed from Figures 1 and 2, the inside face of the side wall of the drawer is provided with a rigid holding stud 9 adapted to cooperate with a holding arm 10 pivoted as at 11 to the inside face of the wing 6. At one end the 35 arm 10 is formed with a head 12 provided with a nose 13 and a shoulder 14 while the opposite end is provided with a laterally offset portion 15 adapted to operate in a slot 16 in the wing. The said laterally offset portion 15 is provided with the 40 spring fingers 17 and 18 which extend to opposite sides thereof. Normally, the spring finger 17 engages the inside face of the drawer head while the other finger 18 is intended to be engaged by the deflected portion 18^a of the plate D when the 45 filing space is crowded as shown in Figure 3.

The object of the arm 10 and its associated parts together with the stud 9 or its equivalent is to releasably hold the drawer head in its closed position. That is to say, when the parts are in the 50 position shown in Figure 1, the drawer head is not only held in its closed position by the force of the spring 7 but is also releasably held due to the engagement of the shoulder 14 of the arm 10 with the stud 9, the arm 10 being pressed upwardly due to the engagement of spring finger 17 55 with the inside face of the head B. When the drawer head is tilted outwardly as shown in Figure 2, the spring finger 17 serves to prevent the arm 10 from falling downwardly on its pivot 11 and also holds the head 12 of the arm in position 60 to ride against the fixed abutment 9 so that the shoulder 14 may properly move behind the stud when the drawer head is moved to its fully closed position.

When the drawer head is closed as shown in 65 Figure 3, and the presser leaf or plate D is forced toward the front of the drawer by the bulk of the filed material, the offset portion 18^a of the plate will engage the spring finger 18 and move the arm 10 upwardly with greater force to ensure 70 engagement of the shoulder 14 with the stud 9, and thereby prevent the expansive force of the filed material from accidentally forcing the drawer head open when it is intended to be closed.

75 The spring fingers 17 and 18 have a tendency

to turn the safety arm 10 in the same direction so that whether the tilting front is open or closed, the arm 10 will always be maintained in position either to engage the stud 9 or directly in engagement with it as the case may be, while at the same time when the drawer is crowded with filing material, the portion 18^a will engage the spring finger 18 and cause the parts 9 and 14 to engage with more force than provided by that of the finger 17 alone. 10

It will, of course, be understood that the arms 18 may be duplicated at opposite sides of the drawer as shown in Figure 5, or, in other words, each wing 6 of the drawer may be provided with holding means for assisting in maintaining the 15 drawer head in its closed position.

In use, the plate D serves to always keep the filing material in orderly fashion and also cooperates with the spring finger 18 of the safety arm or latch 10 to maintain the drawer head 20 closed under abnormal conditions.

Without further description it is thought that the features and advantages of the invention will be readily apparent to those skilled in the art, and it will of course be understood, that changes 25 in the form, proportion and minor details of construction may be resorted to, without departing from the spirit of the invention and scope of the appended claims.

I claim:—

1. In a filing drawer having a bottom and side walls, a tilting drawer head, a front plate pivotally supported at its lower end on the drawer bottom adjacent the tilting head, and means for holding the drawer head in closed position, said means including a holding arm pivotally supported on the tilting head and cooperating with an abutment fixed on a side wall of the drawer, a spring member carried by one end of said arm for normally engaging the tilting drawer head to urge the other end upwardly, and another spring member also carried by said arm and adapted to be engaged by said front plate as the latter is forced toward a vertical position when the tilting drawer head is closed yieldingly to press the arm firmly against the abutment. 40

2. In a filing drawer having a bottom and side walls, a tilting drawer head, a front plate pivotally supported at its lower end on the drawer bottom adjacent the tilting head, means on the 50 upper portion of the front plate for engaging the upper edges of the drawer sides, a spring for normally forcing the plate in a direction to maintain said means in engagement with the drawer sides, and means for holding the tilting head in closed position, said means including a holding arm pivotally supported on the tilting head and cooperating with an abutment fixed on the drawer, a spring member carried by one end of said arm for normally engaging the tilting head to urge 60 the other end upwardly and another spring member also carried by said arm and adapted to be engaged by said front plate as the latter is forced toward a vertical position when the tilting head is closed to yieldingly force the arm firmly 65 against the abutment.

3. In a filing drawer having a bottom and side walls, a tilting drawer head, a front plate pivotally supported at its lower end on the drawer bottom adjacent the tilting head, laterally extending ears on the upper corners of the front plate for engaging the upper edges of the drawer sides, a coil spring mounted coaxially with the pivot for the front plate for normally forcing the plate in a direction to maintain said ears in en- 75

gagement with the drawer sides, and means for holding the tilting drawer head in closed position, said means including a holding arm pivotally supported on the tilting drawer head and co-operating with an abutment fixed on a side wall of the drawer, and a spring member carried by said arm and adapted to be engaged by said front plate as the latter is forced toward a vertical position when the tilting head is closed to yieldingly force the arm firmly against the abutment.

4. In a filing drawer having a bottom and side walls, the combination including, a tilting drawer head adapted to be opened by pulling the drawer forward and to be closed by pushing the drawer backward, a plate pivoted to the drawer independently of and adjacent the drawer head and adapted to be swung on its pivot manually or by the drawer contents, cooperating elements respectively on the drawer and drawer head to hold the drawer head in closed position and means carried by the element on the drawer head and in the path of outward movement of the plate as the latter is forced to a vertical position by the drawer contents to assist in holding the drawer head closed when the filing space of the drawer is crowded.

5. In a filing drawer, the combination including a tilting drawer head adapted to be opened by pulling the drawer forward and to be closed by pushing the drawer backward, a plate pivoted to the drawer independently of and adjacent the drawer head and adapted to be swung on its pivot manually or by the drawer contents, and means carried by the drawer head to assist in holding the same closed, said means including an arm having a shoulder for releasably engaging an abutment on the drawer, a pivot for the arm, an offset portion on said arm at the side of the pivot opposite the shoulder, a leaf spring carried by the offset portion and having oppositely extending fingers, one of which engages the drawer head and the other of which is adapted to be engaged

by said plate, each of said fingers when flexed by the drawer head or plate tending to move the shoulder on the arm toward the abutment.

6. In a filing drawer, a tilting drawer head, a front plate pivoted to the drawer adjacent the drawer head and movable independently of said drawer head, means for limiting the position of the upper edge of said plate inwardly of the filing space of the drawer, cooperating elements respectively on the drawer and drawer head for holding the latter closed, and means on the elements carried by the drawer head adapted to be engaged by the plate when the latter is moved to a more nearly upright position to force said elements in firmly holding engagement.

7. In a filing drawer, a tilting drawer head, cooperating inter-engaging elements respectively on the drawer head and drawer for holding the drawer head in closed position, a movable member normally free of said elements carried by the drawer and adapted to be actuated by the drawer contents; and means, carried by the element on the drawer head, adapted to be pressed by said movable member to urge said inter-engaging elements in tighter gripping relation.

8. In a filing drawer, a tilting drawer head, a front plate pivoted to the drawer, spring means for urging the plate inwardly, means on the plate for engaging the drawer to determine the normal inward inclination of the plate, cooperating elements respectively on the drawer and the drawer head for holding said drawer head in closed position, and means on the tilting drawer head normally spaced from but adapted to be engaged by the front plate as the latter is forced from its normal inclined position toward a vertical position, thereby to urge said cooperating elements in tighter locking relation to prevent the tilting head from being forced open by the drawer contents.

GEO. C. BRAINARD.
